UNITED STATES PATENT OFFICE.

ARTHUR P. WOLFE, OF VINELAND, NEW JERSEY.

RADIATOR-TUBE FOR AUTOMOBILES.

1,146,117.

Specification of Letters Patent. Patented July 13, 1915.

Application filed July 8, 1913. Serial No. 777,863.

To all whom it may concern:

Be it known that I, ARTHUR P. WOLFE, of Vineland, in the county of Cumberland and State of New Jersey, have invented certain new and useful Improvements in Radiator-Tubes for Automobiles, whereof the following is a specification, reference being had to the accompanying drawings.

The invention relates more particularly to a tube which may be used in the construction of radiators for automobiles, through which tube the circulating water for cooling the engine is passed.

An object of the invention is to provide a tube which when embodied in a radiator, will have a large cooling surface, and shaped so as to contain only a relatively thin column of water which is to be cooled.

A further object of the invention is to provide a tube of the above character which is relatively stiff or rigid longitudinally, and which is flexible transversely.

A further object of the invention is to provide a tube of the above character with fins which are so connected to the tube that throughout a greater portion of their surface, said fins are subjected to the cooling air on all sides thereof, at the same time leaving the greatest possible amount of the surface of the tube exposed to the air.

These and other objects will in part be obvious, and will in part be hereinafter more fully disclosed.

In the drawings, which show by way of illustration one embodiment of the invention—Figure I, illustrates an elevation of an automobile radiator having my invention applied thereto. Fig. II, is a perspective view of one of the tubes used in the construction of the radiator shown in Fig. I. Fig. III, is an end view of the said tube.

The invention consists generally in the shaping of the tube so as to form recesses or spaces in the side walls thereof, which extend longitudinally of the tube substantially from end to end thereof. This shaping of the tube gives a relatively large cooling surface on the outer face of the tube, and also contracts the inner surface of the tube so as to form relatively thin channels for the column of water which is passing through the tube to be cooled. The tube is provided with a series of fins preferably formed by a spirally wound wire, which bridges the longitudinally extending recesses or spaces in the side walls of the tube. The wire is sol-

dered to the tube only at the extreme points of the tube. This bridging of the spaces by the fins allows the cooling air to circulate entirely about the fins except at the points where they are attached to the tube and also about the entire surface of the tube with the exception of the said points, and at the same time the contact at the points of attachment of the fins to the tube is sufficient to conduct the heat away from the tubes and permit radiation through the said fins. Each spiral turn is separated from the adjacent spiral turn, and, therefore, the tube as a whole with the fins attached thereto is transversely flexible, while longitudinally it is rigid or stiff.

In Fig. I, I have illustrated the tubes in a vertical position in the radiator but do not wish to be limited in this, since their function would be identical in either vertical or horizontal position. These tubes may be soldered or otherwise secured to headers in the usual manner.

Referring more in detail to the drawings, my improved radiator tube consists of a tube proper 1, which is bent or shaped so as to provide two walls 2, and 3, inclined to each other, thus forming a recess or space 4, which extends longitudinally of the tube, from end to end thereof, as shown in the drawings. On the opposite side of the tube the same is bent or shaped to form walls 5, and 6, which are inclined to each other to form a space or recess 7. The tube is also bent to form inclined walls 8, and 9, thus forming a third space or recess 10, and on the opposite side there is a fourth space or recess 11, formed by the inclined walls 12, and 13. The inclined walls are so disposed relative to one another as to form two relatively narrow channels 14, and 15, which cross each other, and through these spaces circulates the water which is to be cooled.

My improved tube is adapted to be used in a radiator either in a horizontal position or in a vertical position as above noted. As shown in Fig. I, these tubes are joined at their ends to headers 20, and 21, so that the water in the headers will pass through the tubes in the well known manner in this type of radiator.

From the above construction, it will be apparent that I have provided a radiator tube wherein a relatively thin column of water which is to be cooled, passes through the tube, and the tube is formed with a rela-

tively large cooling surface. Surrounding the tube are a plurality of fins 16. These fins are preferably formed by winding a wire spirally about the tube, so that each 5 spiral turn is spaced from the adjacent spiral turn, as clearly shown in Fig. II, of the drawings. The ends 17, of the wire may be soldered to the side walls of the tube, and each spiral turn is also soldered to the extreme 10 points of the tube. The wire, as clearly shown in the drawings, bridges the spaces 4, 7, 10 and 11, so that the wire is out of contact with the tube throughout a greater portion of its length. It will be noted 15 that the channels 14, and 15, formed in the tubes by the spaces 4, 7, 10, and 11, taper toward their outer ends and points of securing the fins are only tangential in character. This permits a free circulation of the air 20 about these points of contact, where it is absolutely essential, owing to the fact that the greater portion of the heat traveling toward the corners of the tube is given off to the fins at these regions. By this construction I have provided fins which are attached to the tube at the extreme outer points thereof, and which are free from the tube throughout the remainder of the length of the fins. The heat absorbed 25 from the water by the tube will be conveyed to the fins, and the air circulating freely and entirely about the fins where they bridge the spaces referred to, will efficiently keep said fins cool. The fins, as above noted, are spaced from 30 one another, and this permits the tube to be to a certain extent, flexible transversely. This flexibility of the tube facilitates the insertion of the tubes in the headers, while the tubes longitudinally are rigid and stiff. 35

40 From the above construction, it will be apparent that there are columns of air passing through each of the spaces 4, 7, 10, and 11, and this air not only quickly and efficiently cools the fins, but also comes directly into contact with practically the entire surface of the tube, because the wire fin only touches the tube at a few small points, (in this case four to each turn). The

amount of contact thus afforded is sufficient to establish the required conduction of the 50 heat from the surface of the tube to the fin, while the reduction of these points of contact to the small amount of surface which is accomplished by the construction leaves almost the entire surface of the tube exposed for the purpose of radiation and likewise almost the entire surface of the fin free 55 for the same purpose. Furthermore, by this constriction, wherein the fins are spaced from one another and the tube is formed as 60 above described, the tubes may be secured rigidly at their ends between the headers and yet they will expand sufficiently to compensate for the freezing of the water without bursting. 65

It is obvious that minor changes may be made in the details of the construction and the shaping of the parts without departing from the spirit of the invention, as set forth in the appended claims. 70

Having thus described my invention, I claim:

1. The combination of a radiator tube having inwardly bent portions extending longitudinally of the tube, and fins extending transversely about the tube, attached tangentially at the extreme points of the tube only, and bridging the intervening recesses formed in the outer faces of the tube by said bent portions. 75

2. A radiator tube having inwardly bent portions extending longitudinally of the tube, with a wire wound spirally about said tube touching it only at the extreme points and bridging the intervening recesses, each 80 spiral turn of said wire being separated from each adjacent spiral turn. 85

In testimony whereof, I have hereunto signed my name at Philadelphia, Pennsylvania, this twenty-seventh day of June, 90 1913.

ARTHUR P. WOLFE.
